CLAIM

The ornamental design for a bulkhead door, as shown and described.

DESCRIPTION

FIG. 1 is a perspective view of a bulkhead door showing my new design wherein the bulkhead door is located in a closed position thereof on a foundation that is illustrated in broken lines;

FIG. 2 is a top plan view thereof;

FIG. 3 is an elevational view of one side thereof;

FIG. 4 is an elevational view of the other side thereof; and, FIG. 5 is a front elevational view thereof.

The broken lines showing the foundation is for illustrative purposes only and forms no part of the claimed design. The rear and the bottom of the bulkhead door forms no part of the claimed design.
